UNITED STATES PATENT OFFICE.

HERBERT A. WRIGHT, OF DETROIT, ASSIGNOR, BY DIRECT AND MESNE ASSIGNMENTS, OF TWO-THIRDS TO WALTER M. REASON, TIMOTHY C. QUINN, ARTHUR T. SLAGHT, LUKE H. CORCORAN, AND JOHN F. SEELEY, ALL OF CARO, MICHIGAN.

TYPE-WRITING MACHINE.

SPECIFICATION forming part of Letters Patent No. 449,021, dated March 24, 1891.

Application filed February 12, 1890. Serial No. 340,202. (No model.)

To all whom it may concern:

Be it known that I, HERBERT A. WRIGHT, of Detroit, in the county of Wayne and State of Michigan, have invented a new and useful

5 Improvement in Apparatus for Operating the Platen and Paper-Carriage of a Type-Writing Machine, of which the following is a specification.

10 My invention consists in an improved apparatus for operating the platen and paper-carriage of a type-writing machine hereinafter fully described and claimed.

Figure 1 is a plan view of a type-writing machine. Fig. 2 is a section of the top plate 15 of the machine and the paper-carriage frame, taken on the line *x x*, Fig. 1, looking from the right. Fig. 3 is a section of the machine on the line *y y*, Fig. 1, looking from the front, the paper-carriage being removed and the 20 upper portions of the hangers supporting the ribbon-spool actuating-bar being broken away. Fig. 4 is a rear elevation of the machine, the paper-carriage being removed.

Fig. 5 is an enlarged section of the rear portion 25 of the machine on the line *z z*, Fig. 1, the paper-carriage being removed. Fig. 6 is an elevation of a part of the paper-carriage-actuating apparatus removed from the machine. Fig. 7 is an isometric view of a portion of the 30 paper-carriage-actuating apparatus not shown in Fig. 6. Fig. 8 is a detail view of the double cams. Fig. 9 is a detail view illustrating one of the operations of the device. Fig. 10 is an elevation showing a modification of the paper- 35 carriage-actuating mechanism. Figs. 11 and 12 are enlarged detail views of the platen-turning apparatus, as shown in Figs. 1 and 2, and Fig. 13 is an enlarged detail section of the rod similar to that shown in Fig. 5.

40 In all the views the type-hammers and the rods connecting them with the levers are omitted.

The object of my invention is to move the 45 paper-carriage transversely across the machine to provide for the spacing of the letters and words, to return said carriage to the position for commencing a line either automatic-

cally or by pressing upon an auxiliary key provided for that purpose, and to automatically turn the platen to provide for the spacing of the lines. 50

The device is shown in the drawings applied to the kind of machine called "The Double-Cased Remington." Its application to other machines of the same general type 55 will, however, be obvious.

My invention is described as follows, reference being had to the accompanying drawings.

A is the frame, and B the top plate, of a 60 type-writing machine.

C are the keys. D is the spacing-bar, and E the levers upon which the keys and spacing-bars are mounted.

F is the frame of the paper-carriage. 65 G is the rod for guiding the motion of the paper-carriage.

H H are journal-lugs extending from the frame F of the paper-carriage and passing around the guide-rod G. 70

At I is placed the usual helical spring, which draws by means of a strap or cord i upon the paper-carriage. Said spring, when used in connection with my invention, is placed at the right of the machine and acts 75 to draw the paper-carriage toward itself to the position for commencing a line of the manuscript upon the platen.

J is a rod a little longer than the distance traveled by the paper-carriage. 80

j j are journal-lugs of equal length extending from each end of the rod J at right angles thereto and holding said rod parallel to the guide-rod G. The journal-lugs j j are provided with circular holes in their ends in which 85 the guide-rod G can turn and slide. The distance between the inside faces of the lugs j j is equal to the distance between the outside faces of the lugs H H.

a, Fig. 7, is a rectangular slot formed in the 90 lower edge of the rod J throughout its entire length.

K is a horizontal rack-bar secured to the forward side of the rod J.

11 are screws passing through slots *k k*, cut through the rack-bar *K* and into the rod *J*. By means of the screws 11 and the slots *k k* the rack-bar has a vertical movement, but is restrained from any horizontal movement relative to the rod *J*. The lower edge of the rack-bar *K* is provided with teeth adapted to engage with the teeth of the wheel.

10 *S L L* are springs secured at one of the journal-lugs *j j* and at the other ends pressing upward upon the rack-bar *K*.

15 *o o* are screws passing through the journal-lugs *j j* and engaging with the springs *L L* to adjust the pressure of said springs upon the rack-bar *K*.

20 *M M*, Fig. 8, are cams pivoted to the rod *J* just above the rack-bar *K* and provided with arms *m m*, by means of which arms the cams may be turned. The springs *L L* press the upper edge of the rack-bar *K* up against said cams *M*.

25 *N* is a horizontal rod pivoted to the ends of the arms *m m* and holding said arms parallel to each other.

25 *n* is a lug extending vertically downward from the center of the rod *N*.

30 *b* is a lug extending from the face of the rack-bar *K* and adapted to limit the motion of the arms *m m*, so that they shall not swing to the left beyond the perpendicular.

35 *P P* are metal strips provided with longitudinal slots and screws passing through said slots into the top plate of the machine, whereby said strips may be adjusted to different positions in the direction of their lengths. *p p* are lugs formed at the ends of said strips, which are toward each other. The strips *P P* are so located upon the top plate of the machine that the lugs *n* shall strike against the 40 lugs *P P* when the paper-carriage is near either end of its travel.

35 *Q*, Fig. 4, is a horizontal slot cut in the rear face of the rod *J* and extending the entire length of said rod.

45 *q* is a pin secured rigidly to the top plate of the machine at its lower end near the back of said top plate and midway between its two sides. The top of the pin *q* is bent to a horizontal position and extends into the slot *Q*, 50 whereby the rod *J* is held in one horizontal plane.

R is a metal plate.

55 *r r* are screws passing through holes in the plate *R* and secured to the top plate of the machine.

s s are spiral springs passing around the shanks of the screws *r r* and pressing the plate *R* against the under surface of the top plate of the machine.

60 *S* is a toothed wheel mounted in a hanger *T* and extending through a slot in the top plate of the machine to engage with the teeth on the lower edge of the rack-bar *K*.

65 *t* is a circular series of teeth formed upon the inner face of the wheel *S*. The faces of the teeth composing said series, which face in a positive direction, are perpendicular to the

plane of the wheel and the other faces are slanting.

U is a lever pivoted at one end to a hanger 70 *u* upon the plate *R*.

V is a spiral tension-spring secured at one end to the plate *R* and at the other end to the free end of the lever *U*.

75 A pawl (indicated by dotted lines at *Y*) is secured to the side of the lever *U* which is toward the wheel *S* and is adapted to engage with the teeth *t*.

W is a ribbon-spool-actuating rod supported in the usual manner in hangers *v v*.

80 *w w* are arms. Each of said arms is secured to the rod *W* by an eye passing over said rod, so that said arm may turn independent of said rod and so that said rod may be moved longitudinally in said eye to the motion of the ribbon-spools. The other end of each of the rods *w w* is immovably secured to the rod *X*, which rod is held in a horizontal position by said arms. The arms *w w* are placed a distance apart which brings them 85 against the interior faces of the hangers *v v*.

85 *Z* is a rod connecting the center of the lever *U* with the rod *X*.

90 *2* is the usual rod extending transversely under the type-key levers at the rear of the 95 machine.

95 *3 3* are wires connecting the ends of the rod 2 with the ends of the rod *X*.

100 *4* is an auxiliary key constructed like the type-keys and located at the side of the machine outside of the yoke formed by the rod 2 and wires 3 3.

105 *5* is a lever pivoted to one side of the frame of the machine at the rear and extending horizontally toward the other side of the machine.

110 *6* is a wire extending perpendicularly from the auxiliary key 4 and connecting said key with the movable end of the lever 5.

115 *7* is a rod connecting the lever 5 with the hanger *T*.

120 *8* is a rack-bar supported by the plate *R* upon standards 9 9. Said standards pass through holes in the top plate of the machine and support said rack above said top plate and in a slot *a* in the rod *J*. The teeth of the rack-bar 8 have perpendicular faces toward the left-hand side of the machine, the other faces of said teeth being slanting.

125 *10*, Fig. 5, is a pin adapted to reciprocate in a vertical aperture at the center of the rod *J* and engaging at its lower end with the teeth of the rack 8 to form a detent, thus preventing any accidental movement of the paper-carriage toward the right of the machine.

130 *11* is a vertically-extending slot through the face of the rod *J* into the aperture at the top of the pin 10.

135 *12* is a pin extending from the top of the pin 10 over and resting upon the upper edge of the rack-bar *K*.

140 *13* is a spiral spring in the aperture above the pin 10, adapted to press downward upon the top of said pin.

145 *14* is a hanger extending from the plate *R*

and having a slot in it in which the lever U plays. The ends of said slot limit the motion of the lever U.

The operation of the above-described device is as follows: When a type-key or the spacing-key is struck, the rod 2 is forced down, carrying with it the rod X by means of the wires 33, the arms *w w* turning about the ribbon-spool-actuating rod W. The shaft 10 X draws the lever U down by means of the rod Z. The pawl upon the lever U is thus caused to engage with another of the teeth *t*. When the key is released, the spring V draws the rod U up again, turning the wheel S one-tenth of an inch (the distance between two adjacent letters upon a type-written manuscript.) The wheel S drives the rack-bar K to the left a distance equal to its own peripheral movement, thus moving the paper-carriage of the machine. When the paper-carriage nears the position corresponding to the end of a line of the manuscript, the lug *n* comes into contact with the lug *p* at the left of the machine, the arms *m m* are turned, 25 thereby turning the cams M M, as shown in Fig. 9. The springs LL then raise said rack-bar, carrying its teeth out of engagement with the teeth of the wheel S. The rack-bar K in rising lifts the pin 12, raising the pin 30 10 out of engagement with the teeth of the rack-bar 8. The paper-carriage, now being free to move toward the right of the machine, is drawn rapidly to that position by the spring I, acting in a manner entirely analogous to 35 the manner in which it has heretofore acted to draw the paper-carriage to the left-hand side of the machine. When the paper-carriage approaches the right-hand side of the machine, the lug *n* strikes against the lug *p* 40 at that side of the machine, the cams M M are turned, thereby forcing the rack-bar K down until its teeth again engage with the teeth of the wheel S, and the pin 10 is driven down by the spring 13 until the lower end of 45 said pin again engages with the teeth of the rack-bar 8. Should it be desirable to return the paper-carriage to the right-hand side of the machine before a line is completed, the operator presses upon the auxiliary key 4, 50 drawing down upon the lever 5 and upon the rod 7, thus drawing the plate R down along the guide-screws *r r*, thus carrying the teeth of the wheel S out of engagement with the teeth of the rack-bar K and the teeth of the 55 rack-bar 8 out of engagement with the end of the pin 10, after which the paper-carriage is returned to the right-hand side of the machine, as before described.

The wheel S and lever U may be replaced 60 by various equivalent devices—as, for instance, that shown in Fig. 10, in which S' is a pair of toggle-levers pivoted at one end of the plate R and at the other end to a block or cross-head 15, sliding in guides in a slot 65 through the plate R. 16 is a pawl upon the block 15, which extends through a slot in the top plate of the machine and engages with

the ratchet-teeth of the rack-bar K. The rod Z is pivotally secured at the junction of the toggle-levers S'. 17 is a swinging frame depending from the plate R. V' is a spring acting to press upward on the rod Z, its lower end being supported by the cross-bar of the swinging frame 17. Instead of the swinging frame 17 and spring V', a spring secured at 75 one end to the plate R and at the other end to the arm *w*, as shown in dotted lines in Fig. 5, may be used.

The mechanism by which the platen is automatically turned to provide for the spacing of the lines of the manuscript is described as follows: 18 18, Fig. 1, are the sliding pieces which bear the platen when it is shifted to provide for the writing of upper or lower case letters. 19 is a lever pivoted back of the 85 platen at 20 to that one of the sliding pieces 18 which is toward the right-hand side of the machine and adapted to be oscillated about said pivot in a vertical plane at right angles to the line of motion of the paper-carriage. 90 21 is the usual toothed wheel secured at one end of and concentric with the platen. 22 is a spring-click the movable end of which engages with the teeth of the wheel 21. 23 is a toothed wheel secured to the same axis of 95 the platen and next to the right-hand bearing of said axis. The teeth of the wheel 23 are provided with radial and slanting faces, the radial faces being upward at the portion of said wheel which is toward the rear of the 100 machine. 24 is a pawl adapted to engage with the teeth of the wheel 23 and rigidly secured to a shaft bearing in and passing through the forward end of the lever 19. 25 is a thumb-piece secured to the same shaft 105 as the pawl 24 upon the opposite side of the lever 19 and extending from said shaft toward the front of the machine. 26 is a spring attached at one end of the lever 19 and at the other end pressing upward upon the thumb-piece 25, thus holding the pawl 24 in engagement with the teeth of the wheel 23. 27 is a lever pivoted at 28 to the sliding piece 18 and provided with a lug 29, adapted to limit the upward movement of the forwardly-extending 110 arm of the lever 19. The lever 19 is bent so as to bring its inner end to and parallel to the top plate of the machine. 30 is the sliding piece adapted to limit the motion of the paper-carriage to provide for the desired width of 115 the margin of the manuscript. 31 is a metal plate secured to the sliding piece 30 in a vertical plane parallel to the line of travel of the paper-carriage and having its upper edge in an inclined plane, as shown in Figs. 3 and 4. 125

The operation of the above-described device for automatically turning the platen is as follows: When the paper-carriage is drawn back, as above described, the end of the lever 19, which is toward the rear of the machine, strikes against and rides upon the inclined edge of the plate 31, forcing down the forward end of said lever and turning the wheel 23, and therefore the platen, by means of the 130

pawl 24. The position of the lever 27 determines whether the lines of the manuscript shall be near together or wide apart by limiting the upward movement of the forward arm 5 of the lever 19 in the usual manner. A lug 32 may be formed upon the lever 27, adapted to engage with notches 33 33 to hold said lever in different positions. The rearwardly-extending arm of lever 19 should be slightly 10 bent to the left, as shown in Fig. 1, so that it shall not pass entirely over the plate 31. By pressing upon the thumb-piece 25 the pawl 24 may be disengaged from the teeth of the wheel 23, leaving the platen free to turn.

15 What I claim as my invention, and desire to secure by Letters Patent, is—

1. In combination with the paper-carriage of a type-writing machine, a rack-bar fastened to said carriage and vertically movable 20 in its fastenings, a spring normally urging said rack-bar upward, a ratchet-bar carried on the frame of the machine, and a spring-pin vertically movable in the carriage and adapted

to be raised by the rack-bar in its vertical motion, substantially as shown and described. 25

2. In combination with the vertically-movable rack-bar K, the spring L, the cams M, pressing upon said rack-bar and having downwardly-extending arms m, a cross-bar N, having the lug n, and the two adjustable 30 plates P, each having a lug p, substantially as shown and described.

3. In combination with the paper-carriage of a type-writing machine, having thereon the rack-bar K and spring-actuating pin 35 10, a wheel S, mounted in vertically-movable bearings, a ratchet-bar 8, carried on the frame in which wheel S is journaled, and a key-lever connected to the frame of said wheel, by which said lever S and ratchet-bar 8 may be 40 simultaneously depressed, substantially as shown and described.
